UNITED STATES PATENT OFFICE.

CHARLES F. DIETHER, OF ST. PAUL, MINNESOTA.

VENTILATING APPARATUS FOR RAILROAD-TUNNELS.

SPECIFICATION forming part of Letters Patent No. 728,685, dated May 19, 1903.

Application filed September 28, 1901. Serial No. 76,834. (No model.)

To all whom it may concern:

Be it known that I, CHARLES F. DIETHER, a citizen of the United States of America, and a resident of St. Paul, in the county of Ramsey and State of Minnesota, have invented certain new and useful Improvements in Ventilating Apparatus for Railroad-Tunnels, of which the following is a specification.

My invention relates to improvements in ventilating apparatus, and is adapted more particularly for use in railway-tunnels, depots, and in mines. In spite of precautions heretofore devised life and property are greatly endangered by smoke and gas collecting in tunnels, mines, &c., and it is the purpose of this invention to reduce this hazard.

In the present application my invention is shown applied to a railway-tunnel; and it consists of a conducting passage-way along the top of the tunnel having chimneys projecting above each end to create a draft through the passage-way. This passage-way is perforated to receive the smoke from the locomotive, the perforations being provided with deflectors which project into the passage-way to prevent the escape of the smoke into the tunnel. The passage-way is also provided with two pockets on each side below the perforations to collect the gases and smoke and reduce the opportunity for their return to the tunnel.

In the accompanying drawings, Figure 1 is a longitudinal section of a tunnel and my improved apparatus applied thereto. Fig. 2 is a cross-section of the tunnel and of my apparatus on a larger scale. Fig. 3 is a detail longitudinal section of Fig. 2; and Fig. 4 is a longitudinal section of a tunnel and my improved apparatus, showing the system of piping provided with fans for removing the heavier gases from the passage-way.

In the drawings let A represent the tunnel; B, the conducting passage-way; C, the chimneys, and D a system of piping for the escape of the heavy gases when cooled.

The passage-way is preferably constructed of thin sheet metal, though it is obvious that other material may be used. This passage-way conforms to the top wall of the tunnel and has an inner wall 2, which is perforated at 3 to receive the smoke from the locomotive smoke-stack. The sides 4 of this inner wall are curved, which form tends to impart a roll-

ing motion to the smoke as it escapes from the locomotive and to retain it within the passage-way.

The perforations in the passage-way are provided with deflectors 5, some of which are pointed toward one end and the remainder toward the other end of the passage-way. As shown, the tunnel is slightly inclined, and in such case the deflectors 6 are turned toward the lower end of the passage-way and the deflectors 7 toward the upper end. The direction of the draft through the passage-way varies according to the grade and length of the tunnel. In a very long tunnel having a slight grade the direction of the draft is toward the lower chimney 8 for only a short distance and toward the upper chimney 9 for the remainder of the length. The deflectors 70 point to correspond in direction with the draft, and in a horizontal tunnel half of the deflectors point toward one end of the tunnel and the other half toward the opposite end. The perforations are provided with the walls 10. The surfaces 11 of the walls 10 directly opposite the deflectors are slightly inclined in the direction in which the deflectors point. The passage-way is supported in the tunnel by the brackets 12, which are fastened to the side walls of the tunnel by means of the bolts 13. Other means may of course be employed for this purpose.

The pockets in the passage-way form the main channel to the chimneys for the smoke and gases. The system of piping D is provided for the egress of the heavier gases if they become cold. This system consists of the main pipes 14 and 15, which are laid on the base of the tunnel near each side, and the branch pipes 16 and 17, which connect the main pipes with the pockets E and F.

In operation the locomotive G, which is indicated in broken lines in Fig. 2, enters the tunnel, and the top of its smoke-stack passes directly below the perforations 3 in the passage-way. The draft in the locomotive smoke-stack forces the heated smoke through the perforations and into the passage-way. The smoke and gases may thus pass from the passage-way through the chimneys.

The deflectors tend to direct the smoke into the pockets of the passage-way, also to prevent the smoke escaping from the passage-

way into the tunnel. The heavier gases when they become cold have egress from the passage-way by the system of piping D.

When the tunnel is so long that the natural draft is checked by reason of the cooling of the smoke before it reaches one of the chimneys, the movement of the column in the passage-way may be increased by the use of fires or fans. As illustrated diagrammatically in Fig. 4, the rotary fans 18 are placed in the branch pipes 16 and are revolved by the electric motors 19. These motors are connected with the line conductors 20 in the tunnel.

Having described my invention, what I claim as new, and desire to protect by Letters Patent, is—

1. An improved ventilating apparatus for railroad-tunnels, consisting of a conducting passage-way having inner side walls for the smoke-stack on the locomotive to pass between, chimneys projecting above each end of said passage-way; said inner walls being perforated to receive smoke from said stack, deflectors adjoining said perforations and surfaces opposite said deflectors; said deflectors and surfaces being inclined in the direction of the draft in the tunnel to prevent the escape of the smoke from said passage-way into the tunnel.

2. An apparatus of the class described, consisting in combination, with a railroad-tunnel, of a conducting passage-way, means for supporting said passage-way along the top of the tunnel, and chimneys projecting above each end of said passage-way; the wall of said passage-way being perforated to receive smoke from below and provided with deflectors above said perforations, which are directed toward each end of the passage-way to correspond with the pitch of the tunnel and the direction of the draft in the passage-way.

3. An apparatus of the class described, consisting in combination, with the railway-tunnel, of a conducting passage-way, along the top of the tunnel, having chimneys projecting above each end; the wall of said passage-way being perforated to receive the smoke from the locomotive; the perforations being provided with deflectors which project longitudinally into the passage-way to prevent the escape of the smoke into the tunnel, and a pocket formed on each side of the passage-way, below the perforations to collect the smoke and gases and reduce the opportunity for their return to the tunnel.

4. An improved ventilating apparatus consisting in combination, with the railway-tunnel of a conducting passage-way, means for

supporting said passage-way along the top of said tunnel, perforations in the wall of the passage-way to receive the smoke from the locomotive, deflectors adjoining said perforations some of which point toward one end and some toward the other end of the tunnel, pockets formed on the sides of said passage-way, below the perforations, and a system of piping connected with the pockets from below.

5. A ventilator, consisting of a conducting passage-way having chimneys projecting above each end; the wall of said passage-way being perforated to receive smoke from below and having a pocket on each side below said perforations, a system of piping, consisting of a main pipe and branch pipes connected to each pocket from below, with fans in said branch pipes, and means for rotating said fans.

6. An apparatus of the class described, consisting of a conducting passage-way having a pocket on each side and a curved inner wall, means for supporting said passage-way along the top of the tunnel, perforations in said inner wall and above said pockets, deflectors adjoining said perforations, some of which point toward one end and the remainder toward the other end of the tunnel, and a system of piping, consisting of a main pipe and branch pipes connected with said passage-way from below, fans in said system of pipes, and means for rotating said fans.

7. An apparatus of the class described, consisting of a passage-way having pockets on each side and a curved inner wall, means for supporting said passage-way in the tunnel, perforations in the inner wall of the passage-way to receive smoke from below, and deflectors adjoining said perforations, some of which point toward one end and the remainder toward the other end of the tunnel.

8. A ventilating apparatus for railroad-tunnels, consisting in combination, with a passage-way, means of supporting said passage-way along the top of the tunnel, a pocket on each side of said passage-way, a series of perforations in the wall of the passage-way to receive smoke from below and deflectors adjoining said perforations, some of said deflectors pointing toward one end and some toward the other end of the tunnel to correspond in direction with the draft in the passage-way.

In testimony whereof I have signed my name to this specification in the presence of two subscribing witnesses.

CHARLES F. DIETHER.
